Jeremiah D. Green, Troy, New York, Letters Pa-
tent No. 190, dated July 18th 1849

The Schedule referred to in those Letters patent and
making part of the same.

To all whom it may concern: Be it known that I, Jeremiah D. Green of the City of Troy County of Rensselaer & State of New York have produced a new Ornamental Design for a Parlour Stove, which stove I call the Etna Air Tight, and I do hereby declare that the annexed and accompanying drawing, being part of this specification, is a full and accurate delineation of a Stove constructed after my design, the sides and back not shewn being similar to and symmetrical with the sides and front represented, except that the back has the usual opening and flange for the applying and fitting of the pipe or smoke flue to the stove.

What I claim as my invention and desire to secure by Letters Patent is the combination and arrangement of Ornamental figures and forms represented in the accompanying drawings,

as making an Ornamental Design for a Parlour Stove.
